DESIGN FOR AN OIL COOLING UNIT

Fred M. Young, Racine, Wis.

Application February 7, 1940, Serial No. 90,081

Term of patent 14 years

To all whom it may concern:

Be it known that I, Fred M. Young, a citizen of the United States, residing at Racine, in the county of Racine and State of Wisconsin, have invented a new, original, and ornamental Design for an Oil Cooling Unit, of which the following is a specification, reference being had to the accompanying drawing, forming a part thereof.

Figure 1 is a lid side view, Figure 2 is an edge view; and Figure 3 is a rear end elevational view

of an oil cooler unit showing my new design. The edge shown in Figure 2 is similar to the opposite edge not shown.

The side not shown in Figure 1 is uniform and substantially flat for its entire surface.

I claim:

The ornamental design for an oil cooling unit, as shown and described.

FRED M. YOUNG.
